UNITED STATES PATENT OFFICE.

WALTER WERNER, OF HOOSICK FALLS, NEW YORK, ASSIGNOR TO THE NOBLE & WOOD MACHINE CO., OF HOOSICK FALLS, NEW YORK, A CORPORATION OF NEW YORK.

PAPER-PULPING ENGINE.

Application filed January 20, 1927. Serial No. 162,289.

My present invention relates to paper pulping engines, and the object of my invention is to produce a simple, efficient continuous paper pulping engine, provided with means whereby that part of the paper which has been reduced to the desired fineness will automatically be extracted from the tub of the engine over or through the upper part thereof, thus permitting the continuous introduction of fresh stock thereinto, and preventing the re-working of that stock which has already been reduced to the desired condition. A further object is to extract the fined stock from the tub while the same is being circulated, and without changing the general direction of flow or normal circulation thereof around or in the tub.

With these objects in view, my present invention consists primarily in the peculiar combination, relative arrangement, and design of the more or less well known devices whereby I have accomplished by objects and attained the desired results, and is illustrated in the accompanying drawings, in which:

Fig. 1 is a plan view of my improved continuous paper pulping engine, cover removed.

Fig. 2 is a side elevation, parts broken away.

Fig. 3 is a detail of the separating rack or screen.

The same reference characters refer to the same parts throughout the several views.

Referring to the drawings, which it is to be understood are in a certain sense illustrative only, it will be observed that my improved continuous paper pulping engine consists of a tub 2 provided with a mid-feather 3, and adapted to receive the stock which is to be reduced to pulp and which may consist of books, bundles of newspapers, or baled paper trimmings and the like. The tub 2 is, of course, to be supplied with the necessary water.

Mounted in the tub 2 is a paddle wheel 4, and a whipper 5, each of which is provided with some suitable means whereby it may be forcibly rotated each at the required speed. In Fig. 1 of the drawings these means are indicated as a driving pulley 8 secured on the shaft of the whipper, the paddle wheel being driven from said shaft by a chain drive 7, driving through an intermediate

shaft 9, the gears being so proportioned that the speed at which the paddle wheel 4 will be rotated is less than the speed of the whipper 5. The paddle wheel 4 is mounted in the tub 2, and is so proportioned that the blades thereof extend from curb to mid-feather and when rotated dip deeply into the tub and so induce the water and stock contained therein to be circulated thereabout. The blades on the paddle wheel 4 are preferably set at an angle to the radii of the wheel, substantially as illustrated in Fig. 2, so that when they leave the water any stock which may be in contact with them will be readily discharged from the wheel and little, if any of it be carried over with or by the blades.

Mounted in the tub 2, preferably immediately behind the paddle wheel 4 is a whipper 5, which consists of a hub or core projecting from and spaced about which are a series of spokes 6. The whipper 5 is to be driven at a comparatively high speed, considerably higher than that at which the paddle wheel 4 is driven.

Behind and in close proximity to the whipper 5 is a separating rack or screen 10, which consists of a series of rather closely spaced bars, 10^b, pendent from a supporting bar 10^s.

The pendent bars may be straight vertical bars, but I prefer to curve them in the one plane somewhat as shown in Fig. 2 of the drawings, the curve approximating, that which experience has shown to be proper deflecting curves as used on the hood over the revolving members of such engines.

Immediately behind the screen 10, and just above the normal level of the stock being circulated in the tub, is mounted a trough 12, the forward side of which is comparatively low. The bottom of this trough tilts down toward the discharge end, which in the drawings is shown as being at the opposite side of the tub, but either end of the trough may be the discharge end; and if desired means (not shown) may be supplied whereby a flushing stream of water will be introduced into the other end of the trough.

The operation of my improved continuous beating engine is as follows: An amount of stock to be beaten, together with the necessary water is introduced into the tub, sufficient to fill it to the usual working level.

Power then being applied the paddle wheel

4 and whipper 5 are rotated and quickly cause the contents of the tub to circulate around the midfeather, and during each circuit the same will be beaten by both the 5 paddle wheel 4 and the whipper 5. The whipper 5 being driven at a comparatively high speed will not only beat the wet paper into a pulp but will also whip it up against the separating rack or screen 10 and a large 10 percentage of such pulp as has been reduced to a sufficiently fined state will pass through the separator and enter the trough 12 and so be carried out of the tub. The water which will be splashed or whipped up by 15 the whipper is usually sufficient to insure the flow of the fined stock out of the trough by way of the discharge end thereof. Any parts of the stock which are too coarse to pass the screen will drop back, or be washed 20 back into the tub and be passed around until it too has been reduced to the desired condition or fineness, and will in turn pass through the screen.

From this described operation it will be 25 evident that as the stock in the tub is reduced to the required fineness it will automatically be extracted therefrom without being subjected to excessive working and that this continual extraction of the stock 30 as soon as it has been sufficiently fined, will permit the continual addition of fresh stock to the tub so that the operation thereof may be continued indefinitely without excessive working of any of the stock which has been 35 deposited in the tub. It will also be evident that any of the coarser stock which may be "whipped" against the separating rack will, if it does not fall of its own weight, be washed off the pendent bars by the continual 40 splash of the water under the urge of the whipper 5.

While no mention has heretofore been made of a "string catcher", this being an appliance which is very generally used in 45 such beating tubs as here described, the use of such a device is contemplated.

I claim:

1. In a paper pulping engine, the combination with a tub having a midfeather, and 50 a propeller adapted to cause circulation of water and stock in the tub, of a rotating whipping device comprising a hub with a multiple series of radially spaced arms projecting therefrom and adapted to beat and 55 whip up stock floating near and on the surface of the water in the tub and project it above the normal level thereof; an extract-

ing trough mounted above said normal level, behind, and a short distance beyond the end of the arms of said whipping device and 60 adapted to collect water and stock projected by said whipping device and automatically deliver it outside of the tub; and a fork-like separating rack interposed between said whipping device and said trough whereby 65 stock which has not been reduced to the desired fineness will be prevented from entering said trough.

2. In a paper pulping engine, the combination with a tub having a midfeather, and 70 a propeller adapted to cause circulation of water and stock contained in the tub, of a rotatable whipping device adapted to beat and whip up stock floating near and on the surface of the water in the tub and to project it above the normal level thereof; an extracting trough mounted above said normal level, behind, and in juxtaposition to the periphery of said whipping device and 75 adapted to receive water and stock projected thereby and automatically deliver it outside of the tub; and a fork-like separating rack interposed between said whipping device and said trough whereby stock not sufficiently fined will be prevented from entering 80 said trough.

3. A continuous paper pulping engine comprising a tub with a midfeather; a propelling device whereby water and stock placed in said tub will be caused to circulate; a whipping device whereby stock floating near or on the surface of the water will be beaten and whipped, and projected above the normal level of the water; an extracting trough located above said normal level, behind and in juxtaposition to the periphery of said whipping device and adapted to catch stock and water projected by said device and 90 automatically deliver it outside of said tub; and a pendent fork-like separating device 100 ahead of said trough and across the path of the water and stock projected by said whipping device.

4. In a paper pulping engine, a tub, a propeller operating therein, an extracting 105 trough arranged above the normal level of the stock floating in the tub, a whipping device operating between the propeller and said trough, and a separating rack interposed between the whipping device and 110 trough for the purpose specified.

In testimony whereof I have affixed my signature.

WALTER WERNER.
